UNITED STATES PATENT OFFICE.

JOSEPH H. COPE, OF DENVER, COLORADO.

HAYSTACKER.

Application filed July 12, 1921. Serial No. 485,720.

To all whom it may concern:

Be it known that I, JOSEPH H. COPE, a citizen of the United States, residing at the city and county of Denver and State of Colorado, have invented certain new and useful Improvements in Haystackers; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in hay stackers or rickers of that class embodying a stacker head or elevating means, carried by lifting arms movably attached to a base-support and operative thru the medium of draft appliances connected thereto to facilitate the formation of a rick or stack. An example of this class of stacker is shown in patent number 924534 granted to me June 8, 1909. The present invention relates 20 specifically to a truck which is attached to the base of the stacker and which is used in transporting the stacker from place to place.

I am aware that it is old to equip the base 30 of a haystacker with wheels to facilitate transportation thereof, and in my patent above referred to, I have shown wheels for this purpose, but when the wheels are secured to the base in the manner shown in 35 my former patent, it usually becomes necessary to dig a hole in the ground for each wheel in order that the base may rest solidly on the ground; this necessitates the performance of considerable extra labor besides when it is desired to move the stacker the holes are an impediment, which greatly increases the labor required to do so.

It is the object of this invention to provide a truck for this type of haystacker, that will 45 permit the base to rest solidly upon the ground without the necessity of digging holes therein to accommodate the wheels. The relationship between my truck, the base and the lifter frame is such that the latter

will automatically raise the base from the ground and cause it to be supported on the truck whenever it is desired to do so, thereby dispensing with the necessity of heavy lifting.

I will now describe my invention in detail 55 by reference to the accompanying drawings in which

Fig. 1 is a plan view of my improved stacker with the truck in operative position.

Fig. 2 is a side elevation of the same. 60

Fig. 3 is a side elevation of my stacker with the truck in inoperative position.

Fig. 4 is a side elevation showing the base of the stacker resting on the ground and the lifter frame in extended vertical position. 65

Fig. 5 is a detail showing the construction of my truck, and

Fig. 6 is a detail of the sliding connection between the arms of the lifter frame. 70

In the drawings the same reference characters represent the same parts throughout the several views.

Let the numeral 5 represent in its entirety the base, which consists of two parallel 75 bars 6, (shown in the drawing as built up of two separate pieces *a* and *b*), which are held in spaced relation by transverse bars 7, 8, and 9, and in angular relation by braces 10. Secured to the forward end of the base 80 5 is a vertical frame consisting of uprights 11, which have their lower ends bolted to cross piece 9, and their upper ends connected by a transverse horizontal bar 12; this frame is held in its vertical position by 85 diagonal braces 13, each of which comprises two bars bolted to opposite sides of the top portion of upright bars 11, and have their lower ends bolted to opposite sides of bars 6. Each of said diagonal brace bars 13 has 90 one end of a brace 14 secured thereto by notches, or otherwise, and the other end secured to the base member 6 by bolts or similar means. Pivotally connected between each pair of braces 14 by means of a bolt 15 95 is one end of bars 16, which form the sides of the pivoted lifter frame. Bars 16 are held in spaced relation by transverse bars 17 and

18, and in angular relation by diagonal braces 19. Near the outer end of each bar 16 is a long narrow slot 20 the upper side of which is formed by an iron bar 21 held in place on bar 16 by bolts 22, all as shown in detail in Fig. 6. Sliding in slots 20 are flat iron bars 23 whose inner ends are bolted to a transverse bar 24, and whose outer ends are provided with an eyelet for the reception 10 of one end of springs 25, the other ends of which are anchored to bar 16 by means of eyelets 26, which are secured thereto by bolts 27. The bar 24 and springs 25 form a resilient stop or buffer and cooperate with the 15 other elements in a manner to be hereinafter described.

Slidingly connected to bars 16 are bars 28, which form the stacker head frame. The upper or outer ends of bars 28 are held in 20 spaced relation by transverse bars 29 and 30, which form part of the stacker-head 100. Secured to the lower ends of bars 28 are hooked members 31, which hold them in 25 slidable engagement with bar 16 and secured to transverse bar 18, are hooked members 32 whose hooked ends are in engagement with bars 28. This connection permits 30 of free sliding movement between bars 16 and 28, and at the same time holds them securely in a predetermined relation.

Secured to each side of the inner ends of bars 6 is a steel plate or bar 33 to the upper ends of which is pivoted, by means of a bolt 34, a link 35 the upper end of which passes 35 between the brace members 13 and is guided thereby. Pivottally attached to the upper end of link 35 is another link member 36 the other end of which is pivottally attached by a removable pin 37 to the sliding stacker 40 head frame bars 28. The bars 28 are provided with a plurality of holes 38 for the reception of pivot pin 37, whereby the link 36 may be secured to bars 28 at various 45 points in order to vary the lift of the stacker-head in a manner that will hereinafter appear. Links 36 are each provided with a depending stop 39, the object of 50 which is to engage the ends of transverse bar 24 and tension the springs 25 and thereby produce resilient buffer action at the end of each upward throw of the stacker-head.

In order to raise the stacker-head 100, and cooperating frame, and move the same about the pivots 15, I have provided an A 55 frame 40 which comprises two main frame members 41, held in spaced relation by cross bars 42 and 43, the whole being pivottally mounted on the base bars 6 by means of pivots 44.

Secured to the top of the A frame and 60 pivottally mounted between the ends of the same on a bolt 45 is a pulley 46 and a U-shaped anchoring member 47, as well as an anchoring device 48. Secured to the 65 anchoring device 48 are two tension rods

whose lower ends are pivotally connected to the outer end of bars 16 at point 50. Having their lower ends secured to the lower ends of braces 13 by one of the bolts that holds the latter to bar 6 are brace members 70 51. The upper ends of braces 51 are held together by a bolt 52, which also serves as a pivot for pulley 53. To the top of the framework formed by members 11, 12 and 51 are secured two Z-shaped members 54 75 which are pivoted to said framework by a bolt 52. Bars 51 have their lower ends secured to the base members 6, and with members 11 form a triangular structure which is rigid. The ends 56 of members 54 80 have a bolt 57 joining them, the same being true for the other ends 58. The function performed by parts 56 and 58 being to guide the rope and to prevent it from jumping off from the pulleys.

A rope 59 has one end secured to the U-shaped anchoring member 47 and passes thence over pulley 55, thence back to and around pulley 46, thence over pulley 53 and down to and around pulley 61, whence it 90 passes outwardly to one side of the frame.

If a horse is hitched to the end of rope 59 and made to exert a sufficient pull thereon, A frame 40 will be rotated on its pivots 44, and since the tip of this frame is connected 95 to the stacker-head frame by means of rods 49, the latter will be caused to rotate about its pivots 15 until the parts finally assume the position shown in Fig. 4. It will be noted here that as the stacker-head frame 100 rotates about pivots 15, link 36 whose inner end is pivotally connected to the upper end of link 35 and consequently stationary, thru its pivotal connection with bar 28, at 37, causes the latter to slide along bar 105 16 and thus extend the stacker-head lifting frame. When the lifting frame approaches the position shown in Fig. 4, stops 39 engage the ends of bar 24 and put springs 25 under tension which increases as the lifting 110 frame continues to move about its pivots until finally bars 23 reach the end of the slot 20 and form a positive stop.

I desire to call attention at this point to the action of member 54 in keeping the rope 115 from "jumping" off the pulleys 53 and 55. This member has been so designed that the part 56 projects over the sides of the pulley at the point where the rope is tangent thereto, and maintains this relationship as 120 the pulley 46 moves about its pivot 45, being held in this relative position by the tension of the ropes passing over pulley 55.

In order to facilitate moving, I have provided the outer end of the base with a two 125 wheeled truck. The wheels 62 are mounted on an axle 63, which passes thru holes in the sides of suitable angle bars 64, which have one end pivoted to a block 65 secured by bolts 66 to transverse bar 7. The other 130

- end of angle bars 64 are secured by bolts 67 to a transverse bar 68 and are held in proper right angular relation therewith by means of braces 69^a. Slidably connected to bar 68 by means of a U-shaped strap 69 are short bars 70 one end of which rests upon the projecting ends of the angle irons 64. When bars 70 occupy the position shown in Fig. 5, the stacker-head frame may assume the position shown in Fig. 3 with the tines of the stacker head resting on the ground and the base frame also resting on the ground; this is the proper position for operation. When it is desired to move the stacker, the stacker-head frame is raised and bars 70 shoved out to the position shown in dotted lines in Fig. 5, the stacker head frame is then lowered and will rest upon the projecting ends of bars 70, and, since the stacker head and frame are of considerable weight, they overbalance the weight due to the base frame, and lift the latter off the ground as shown in Fig. 2. Since the wheels are placed in such a position that the axles are almost directly beneath the center of gravity, the inner end of the stacker will rest upon the ground with but little weight, the stacker can therefore be easily moved by merely hitching a horse or a team of horses to the inner end thereof. When the stacker has been moved to its new location the stacker head frame is raised sufficiently to permit the base frame bars 6 to rest upon the ground, the bars 70 are then withdrawn to the position indicated in full lines in Fig. 5, and the stacker is ready to operate.
- Having now described my improved haystacker what I consider as new, and claim as my invention or discovery is:
- 40 1. In a haystacker, in combination, a base frame, a stacker head lifting frame pivotally attached thereto, a truck pivotally attached to said base frame, and means, whereby the weight of the stacker head lifting frame, will automatically raise one end of the base frame from the ground and support the same on the truck wheels.
  2. In a haystacker, in combination, a base frame, a stacker head lifting frame pivotally attached thereto near the inner end thereof, a truck pivotally attached to said base frame near the outer end thereof and means whereby the weight of the stacker head frame will automatically raise the outer end of the base frame from the ground and support the same on the truck whereby the haystacker can be readily moved.
  3. In a haystacker, a base frame comprising longitudinal supporting bars and transverse spacing bars, a truck frame pivotally attached to said base frame near one end thereof, wheels pivoted to said truck frame and means for raising said base frame and supporting one end thereof on the truck.
  - 65 4. In a haystacker, a base frame comprising longitudinal supporting bars and transverse spacing bars, a truck frame having two wheels pivotally attached thereto, said base frame being pivotally attached to said truck frame at such a distance from the wheel that the base frame may rest upon the ground and means for automatically raising one end of said base frame and supporting the same on the truck.
  5. In a haystacker, in combination, a base frame, a stacker head lifting frame pivotally attached thereto near the inner end thereof, a truck frame pivotally attached to said base frame, said truck frame being provided with means that may be projected into the path of the stacker head frame or withdrawn therefrom at will, said means being on the opposite side of the axle from the pivotal connections, whereby the weight of the stacker head frame resting upon said projections will tilt said truck frame and raise the end of the base frame from the ground.
  6. In a haystacker, in combination, a base frame, a stacker head lifting frame pivotally attached thereto and a truck pivotally attached to said base frame, said truck comprising two pairs of bars spaced apart, a wheel between each pair and pivoted intermediate the ends thereof a transverse bar secured to the ends of each bar of the two pair, diagonal braces from said transverse bar to each of said pairs of bars and slidably members attached to the ends of said transverse bar and adapted to be projected into the path of said stacker head and lifting frame.
  7. In a haystacker, in combination, a base frame, a stacker head lifting frame pivotally attached thereto, a truck frame pivotally attached to said base frame near one end thereof, means on said truck frame slidable thereon for projection into the path of said lifting frame, means for turning said lifting frame on its pivots, said means comprising an A frame pivoted to said base frame, means connecting the top of said A frame with the lifting frame, a pulley pivoted to the top of said A frame, another pulley secured to the end of the base frame, a rope connecting said pulleys, guiding means cooperating with said last named pulley, said guiding means comprising two Z shaped members, one on each side of the pulley and means whereby the guiding means projects over the edge of the pulley at the point of tangency of the rope in every position of the latter.
  8. In a haystacker, in combination, a base frame, a stacker head lifting frame pivotally attached thereto, a truck and means cooperating with said frames for automatically raising one end of the base frame and supporting it on said truck.
  9. In a haystacker, in combination, a base frame, a stacker head lifting frame pivotally attached thereto, a truck pivotally attached to the base frame and means cooperating

with said lifting frame for automatically raising the base frame from the ground and supporting said frame on the truck.

10. In a haystacker, in combination, a base frame, a stacker head lifting frame pivotally attached thereto, a truck attached to said base frame, and means whereby the weight

of the stacker head lifting frame will automatically raise one end of the base frame from the ground and support the same on 10 the truck wheels.

In testimony whereof I affix my signature.

JOSEPH H. COPE.
